ABSTRACT OF THE DISCLOSURE

The invention is primarily directed to bearing means for maintaining the cutting edge of a knife in a predetermined relationship to a rotatable cylinder.

The subject invention relates generally to a knife assembly and more particularly is directed to an assembly for cutting or snipping off the ends of a product, such as string beans, which are adapted to protrude outwardly through peripheral openings provided in a cylinder or drum when the latter is rotated.

Machines or equipment for effecting such cutting are exemplified, for example, in my Patent Nos. 2,705,516, dated Apr. 5, 1955; 3,304,974, dated Feb. 21, 1967; 3,304,975, dated Feb. 21, 1967; and in my pending application Ser. No. 461,713, now Patent No. 3,318,350.

The invention, among other things is directed to a knife assembly which includes unique improvements in design and construction over those embodied in the patents and application above referred to.

A significant object of the invention is to provide an organization in which the life of the knives of the knife assembly and a cylinder are appreciably prolonged, as compared to those illustrated in the above patents and application.

More specifically, an object of the invention is to provide an assembly comprising a support for knives, resiliently flexible means for urging the knives toward a rotatable cylinder for cutting the ends off string beans, and means carried by the assembly for bearing engagement with the cylinder for maintaining the knives in a predetermined position relative to the cylinder.

A particular object of the invention is to provide a bearing means which also serves to stabilize the knife assembly and particularly the knives thereof and reduce chatter, vibration, and noise.

A specific but important object of the invention is to provide a bearing means which will substantially prevent a galling or scoring of the peripheral surface of the cylinder and provide a relatively large bearing area for engagement with such surface, as compared to the cutting areas or edge of the knife which may or may not engage such peripheral surface.

The invention also offers advantages with respect to providing bearing means which is preferably of a non-metallic character, one which is resiliently flexible, efficient, more or less self-lubricating, and exceptionally durable for the purpose intended.

Additional objects and advantages of the invention will become apparent after the description hereinafter set forth is considered in conjunction with the drawings annexed hereto.

In the drawings:

FIGURE 1 is a front elevational view of a knife assembly, embodying the invention, carried by a support and operatively associated with a cylinder, with only a portion of the support and cylinder being shown;

FIGURE 2 is a side elevational view of a portion of the structure shown in FIGURE 1;

FIGURE 3 is an enlarged transverse section taken substantially on the line 3—3 of FIGURE 1, showing a unit

2

or assembly comprising a knife and a bearing means preferably secured thereto by cement;

FIGURE 4 is a bottom view of the knife and bearing means shown in FIGURE 3;

FIGURE 5 is an edge elevational view of the structure shown in FIGURE 4;

FIGURE 6 is a bottom view of a modified unit comprising a knife and bearing means, in which fastening means, preferably in the form of rivets, is utilized to connect the components;

FIGURE 7 is a transverse section taken substantially on line 7—7 of FIGURE 6;

FIGURE 8 is a view similar to FIGURE 6 showing a backing or reinforcing member secured against a bearing means; and

FIGURE 9 is a transverse section taken substantially on line 9—9 of FIGURE 8.

Referring to FIGURE 1 of the drawing, there is disclosed a portion of rotatable cylinder 1 and a knife assembly 2 which is operatively associated with the cylinder. In practice, as exemplified in the patent and applications above referred to, a plurality of substantially corresponding knife assemblies is utilized, but only one assembly is depicted in the drawings of the subject application.

The cylinder is provided with rows of circumferentially spaced openings or slots 3 through which the ends of a product, such as string beans, may be caused to protrude outwardly when the cylinder is rotated.

The knife assembly, as exemplified herein, comprises a structure generally designated 4 supporting a plurality of three curved knives 5, attaching means generally designated 6 for detachably connecting the assembly to a horizontal mounting or cylindrical support 7 disposed alongside the cylinder and resiliently flexible means, preferably in the form of a single leaf spring 8 which is detachably connected to the knife supporting structure 4 and the attaching means 6. Obviously, a plurality of leaf springs may be utilized in lieu of the spring 8.

The knife supporting structure 4, which will now be described, may be designed and constructed in various ways but, as illustrated, it is in the form of an articulated frame, preferably cast, and comprises an elongate rigid bar 9 and a plurality of three substantially corresponding equally spaced elongate members 10 and a pair of apertured offsets 11 provided with planar seat means 12 (one shown) for an enlarged apertured extremity 13 of the spring 8. A pair of fastening means, such as bolts 14, extend through the apertures in the offsets 11 and the extremity 13 for firmly detachably connecting the spring to the frame. It will be observed that the members 10 are offset from the bar as indicated at 10' and disposed in a parallel relationship at oblique angles with respect to the longitudinal axis of the bar 9 and that each includes an upper relatively long extremity and a shorter lower extremity.

It will be noted that the rear side of each of the members is provided with a concave seat 15 (one shown) which extends throughout the full length of the member at an inclination with respect to its longitudinal axis. The upper extremity of each of the members is preferably reinforced by a longitudinally extending generally triangular rib 16 which merges into the bar 9 in order to impart strength to the members as well as to the connections between the members and bar. The ends of the members 10 are provided with apertures 17 (one shown) and fastening means preferably in the form of bolts 18 which extend through the apertures 17 and through apertures 19 provided in the extremities of the knives 5, as best depicted in FIGURES 2, 3 and 4. Each of the knives 5 is preferably resiliently flexible, of uniform thickness,

generally rectangular and of a width and length somewhat greater than the width and length of each of the members 10, as shown in FIGURE 1. Each knife is also preferably bevelled at its ends as indicated at 20 and includes an elongate sharpened edge 50 for severing the ends off the beans and a lower end which is bent or angled outwardly, as indicated at 22 whereby to prevent the knives from gouging into the cylinder. Each knife is also preferably bevelled at 51 throughout its length adjacent to the edge 50.

The resiliently flexible means 8 is preferably in the form of a single or individual flat or planar spring of uniform thickness. This spring is substantially uniformly resiliently flexible throughout the major portion of its length and is relatively wide in order to impart stability thereto as well as the knife supporting structure in its relation to the cylinder. The upper extremity of the spring is enlarged at 13, as stated above, and its lower extremity is similarly enlarged as at 23 and provided with apertures for receiving fasteners 35, as will be described more in detail subsequently. It will be observed that the upper extremity 13 of the spring is preferably slightly offset as indicated at 24 whereby to assist in maintaining the knives in a correct attitude for operative relationship with respect to the cylinder.

The attaching means generally designated 6 may be designed and constructed in various ways but, as illustrated herein, it preferably comprises a substantially semi-cylindrical rigid block 25 having an inner substantially semicylindrical surface of appreciable area for receiving and engaging an under side of the cylindrical surface of the support 7. A substantially U-shaped element 27 has a curved portion which engages an upper side of the support and legs 29 which straddle the support and carry nuts 30 for adjustably clamping the support between the block and element. The nuts of the bolts 30 may be readily loosened and tightened to enable an operator to correctly adjust and firmly secure the attaching means on the support 7 so that the spring will apply sufficient pressure to correctly urge all of the edges of the knives toward the periphery of the cylinder for efficiently cutting off the ends of the beans. The spring, due to its uniform thickness, substantially uniform relatively wide width throughout the major portion of its length and enlarged extremities is rendered relatively stable and efficient for substantially everlasting use in maintaining the knife supporting structure in a correct stabilized operative relationship with respect to the cylinder and at the same time afford a setup whereby the structure may be automatically retracted and re-urged toward the cylinder.

As pointed out above the principal object of the subject invention is to provide a knife assembly with bearing means whereby to maintain one or more knives of the assembly in a predetermined operative relationship with respect to the peripheral surface of the cylinder. More explicitly, the invention involves locating or interposing bearing means between the knife supporting structure and the cylinder for the purpose of preventing or minimizing metal-to-metal contact between the knives and the cylinder.

The bearing means for accomplishing the above objective may be designed and constructed in various ways. For example, all of the bearing means exemplified in FIGURES 2 through 9, are preferably elongated, substantially rectangular in cross-section, and, as shown in FIGURES 2 through 5, constructed from a non-metallic material commonly referred to in the industry as urethane. This material or product has proven to be resilient, more or less self-lubricating, non-galling, exceptionally durable from the standpoint of wear, and readily returnable to its original shape or size after distortion or compression.

As exemplified in FIGURES 2 through 5, for example, a bearing means 60 is provided with a bevel or chamfer 61. This bearing means is preferably bonded or otherwise permanently secured against an underside or surface

of the knife 5 by cement 62 or some other suitable bonding agent, as shown in FIGURE 3. The bearing means is preferably of a length substantially corresponding to the length of the knife and the beveled surface 61 is preferably disposed in a plane substantially parallel to the bevel 51 of the knife, as shown in FIGURE 3, so that the bevel of the knife is spaced in a plane substantially parallel to the peripheral surface of the cylinder, the space or gap therebetween being within a range of .005" and .025".

With the above organization, the cutting edge 51 of each of the knives is normally maintained in spaced relationship with respect to the cylinder in order to prevent metal-to-metal contact therebetween and thereby prevent galling and/or scoring of the cylinder. Moreover, the bearing means serve to provide relatively large bearing surfaces or areas which engage the cylinder for the purpose of stabilizing the position of the knives individually as well as jointly. Furthermore, the organization assists in preventing dulling and/or accidentally nicking or damaging of the knife edges.

Referring to FIGURES 6 and 7, there is exemplified a modified structure or unit having a different mode of securing a bearing means 70 to each of the knives. More specifically in this respect, each of the bearing means 70 substantially corresponds to the bearing means 60, except that it is secured to a knife by means of a plurality of fastening means preferably in the form of rivets 71 which extend through aligned apertures provide therefor in the knife and bearing means as clearly shown.

Referring to the modified structure or unit illustrated in FIGURES 8 and 9 of the drawing there is shown a bearing means 80 which substantially corresponds to the bearing means 60 and 70 above referred to. The bearing means 80 is preferably secured to a knife by a plurality of rivets 81 which extend through aligned apertures provided therefor in the knife and bearing means and also through apertures provided in a backing or reinforcing member 83. The backing members respectively serve to more firmly secure or anchor the bearing means in relation to the knives.

Attention is directed to the fact that although an objective of the invention is to primarily maintain the cutting edges of the knives in spaced relation to the cylinder, it is to be appreciated that the bearing means after long and hard usage may become worn to an extent whereby the bevels of the knives will become aligned with the wearing surfaces of the bearing means and bear against the cylinder. More specifically, the worn surface of the bearing means 80 is illustrated by a dotted line 84 in FIGURE 9. Otherwise expressed, the bearing means, irrespective of whether they do or do not space the cutting edges of the knives in relation to the cylinder do in fact provide substantial bearing surfaces or areas which serve to prevent and/or minimize wear between the knives and cylinder and efficiently stabilize the knife supporting structure and knives and particularly the cutting edges of the latter. The bearing means also serves to reduce friction between the knife assembly and cylinder.

In addition to the above, and insofar as known, all commercial bean snipping machines that have been built by anyone have had knives in contact with a rotating cylinder. The knives have been made of either carbon knife steel or stainless knife steel and the cylinders have been made of either ordinary steel, stainless steel, bronze or plastic. The most serious problem with such machines has been that the knives wear the cylinder until it becomes useless within a relatively short time. No suitable material acting as a lubricant can be used because any such material will contaminate the food product. Water is the only known liquid that can be used on this equipment at the time green beans are being processed. In this application, water proves itself to be a poor lubricant.

Although bean snipper cylinders are being made of plastic, no plastic has yet been found with sufficient

rigidity and strength and yet remain a good wearing material with sharp knives running against it. Unfortunately, when selecting the best materials for both the cylinder and the knives, the two materials are not compatible for rubbing against each other.

Having thus described my invention, it is obvious that various other modifications may be made in the same manner without departing from the spirit of the invention and, therefore, I do not wish to be understood as limiting myself to the exact forms, constructions, arrangements, and combinations of parts herein shown and described.

I claim:

1. In combination: a cylinder having a cylindrical wall provided with a plurality of openings whereby ends of elongated items adapted for movement in the cylinder may extend therethrough, a support, an elongated knife secured to said support and provided with an elongated cutting edge for snipping off such ends, means for urging the support and knife toward said wall, and elongated bearing means secured in relation to an under surface of said knife and extending lengthwise thereof engaging said wall for locating said cutting edge in a predetermined position with respect thereto.

2. In combination: a cylinder adapted for rotation and having a cylindrical wall provided with a plurality of openings through which ends of a multitude of items adapted for movement in the cylinder may project, an assembly comprising a support and a knife carried by said support having a cutting edge for cutting off such ends, means for urging the assembly toward said wall, and means carried by said assembly providing a substantial bearing surface engaging said wall for maintaining said cutting edge in a predetermined position with respect thereto.

3. In combination: a cylinder adapted for rotation and having a cylindrical wall provided with a plurality of openings whereby elongated products disposed in the cylinder and having ends may protrude through said openings, a support carrying a knife having a cutting edge for cutting off such ends, means for urging said support and said knife as a unit toward said cylinder, and means carried by said knife and bearing against said cylinder for stabilizing said knife and maintaining its cutting edge in a predetermined relationship to said wall.

4. The combination defined in claim 3, in which said bearing means serves to space said cutting edge a predetermined distance away from said wall.

5. The combination defined in claim 3, in which said bearing means is secured to said knife by cement.

6. The combination defined in claim 3, in which said

bearing means is secured to said knife by fasteners extending through said knife and bearing means.

7. The combination defined in claim 3, including a reinforcement with said bearing means being secured between said knife and reinforcement.

8. The combination defined in claim 2, in which said bearing means is constructed from urethane.

9. Knife structure for use with a rotatable cylinder which has a cylindrical wall provided with a plurality of openings whereby ends of elongated items adapted for movement in the cylinder may extend through the openings, said knife structure comprising a support and an elongated knife secured to said support and provided with an elongated cutting edge for snipping off such ends, means for mounting the support for urging the support and knife toward the wall of such a cylinder, and elongated bearing means secured in relation to an under surface of said knife and extending lengthwise thereof for engaging such a wall for locating said cutting edge in a predetermined position with respect thereto.

10. An assembly for use with a rotatable cylinder having a cylindrical wall provided with a plurality of openings through which ends of a multitude of items adapted for movement in the cylinder may project, said assembly comprising a support and a knife carried by said support having a cutting edge for cutting off such ends, means whereby the assembly may be urged toward such a wall, and means carried by said assembly providing a substantial bearing surface for engaging such a wall for maintaining said cutting edge in a predetermined position with respect thereto.

11. Knife structure comprising: a support carrying a knife having a cutting edge for cutting off ends of items which are adapted to tumble and project through openings in a cylindrical wall of a rotatable cylinder, means whereby said support and knife as a unit may be urged toward such a cylinder, and means carried by said knife for bearing against such a wall for stabilizing said knife and maintaining its cutting edge in a predetermined relationship to such a wall.

12. The structure defined in claim 11, in which said bearing means is constructed from urethane.
